CUT-OUT DIE

Charles E. Hardenbrook, Jr., East Lynn, Mass., assignor to United Shoe Machinery Corporation, Paterson, N. J., a corporation of New Jersey

Application December 22, 1933, Serial No. 703,560

6 Claims. (Cl. 164—93)

This invention relates to a die and is herein illustrated as being embodied in a die for performing cut-out operations upon shoe parts.

In producing ornamental perforations in shoe parts such as quarters or vamps it has been common practice to make use of dies provided with punch tubes so arranged as to produce various geometrical designs and configurations upon forcing the die through a blank. In perforating shoe parts which are to be incorporated in the left and right shoes of a pair it is frequently necessary or desirable to locate the perforations differently in the two kinds of blanks. Various mechanisms have been devised for accomplishing this, most of which make use of "right" and "left" dies. In view of the foregoing, it is an object of the present invention to provide a novel die construction by which the perforating operation can be performed accurately and economically upon either right or left blanks. To this end and as illustrated, the invention comprises a die having a plurality of punch tubes, a work-support overlying the tubes and gaging means mounted upon the work support for movement selectively into position to locate either a right or a left blank in predetermined position relatively to the punch tubes. Preferably, and as shown, the gaging means comprises a mask plate pivotally and hingedly mounted upon a work support in the form of a stripper plate so that the mask plate can be moved to permit insertion of a blank between the two plates and, at the same time, can be moved laterally of the stripper plate and punch tubes to locate either right or left blank gaging portions of the mask plate relatively to the punch tubes.

Dies constructed as above set forth are advantageous in that a single die can be used to perforate both right and left blanks which can be properly located relatively to the punch tubes by readily adjustable means.

Other objects and features of the invention will be apparent from the following detailed description when taken in connection with the accompanying drawing and will be pointed out in the claims.

In the drawing,

Fig. 1 is a side elevation partly in section of a die constructed in accordance with one embodiment of the invention; and

Fig. 2 is a plan view of the die, mask and stripper plates with a blank located in operative position.

As illustrated in Fig. 1, the die comprises a base 10 carrying punch tubes 12, a work support

or a stripper plate 14 overlying the tubes and a mask plate 16 mounted upon the stripper plate for locating a shoe part blank 18 relatively to the punch tubes 12.

The stripper plate is supported by pins 20 positioned in openings 22 in the die base 10, there being springs 24 surrounding the pins 20 normally operative to maintain the stripper plate in position slightly above the edges of the punch tubes 12.

The mask plate 16 is provided with two openings 26 and 28 symmetrically disposed relatively to the center line of the mask plate, each of the openings being somewhat larger than the area covered by the punch tubes 12 so that the punch tubes can operate through the mask plate. Edge portions 30 of the opening 26 are shaped to correspond with portions of a left blank to be operated upon so that such portions may act as a gage for locating the blank relatively to the punch tubes in producing perforations which will be located in predetermined relation to the marginal or other portions of the blank. Similarly, edge portions 32 of the opening 28 correspond to portions of a right blank so that such edge portions can be used to locate a right blank relatively to the punch tubes.

In order to provide for the positioning of the gage portions 30 and 32 of the mask in proper position to locate either right or left blanks, as the case may be, I have mounted the mask plate 16 upon the stripper plate 14 so that it can be moved laterally to locate either of the gage portions in operative position relatively to the punch tubes. To this end the stripper plate is provided with a pivot pin 34 secured to the underside thereof and upon which is mounted a hinge 36 one leaf of which is yieldably held against the under side of the plate 14 by a spring 38 and the other leaf of which is secured to the under side of the mask plate. Lateral movement of the plate 16 is limited by stop pins 40 carried by the plate 14 and arranged to engage the hinge to prevent movement of the plate 16 beyond a predetermined distance in either direction. This construction makes it possible to move the mask plate about the pivot pin 34 laterally of the plate 14 in locating either of the gage portions relatively to the punch tubes 12 and, at the same time, permits the mask plate to be swung out of the way while a blank is placed upon the stripper plate 14.

In order accurately to determine the position of the gage portions 30 and 32 relatively to the punch tubes the stripper plate 14 is provided

with a pin 42 located along the center line of the plate, and the mask plate 16 is provided with two holes 44 and 45 which are so positioned relatively to the openings 26 and 28 that when the mask plate is located with the pin 42 in one of the holes the gaging portions 30 or 32 will be in operative position relative to the punch tubes 12. In Fig. 2 the full lines show the mask plate in position for operation upon right blanks and the broken lines indicate the mask plate in position for operation upon left blanks.

The die is adapted for use in cut-out machines of a type which is indicated generally in Fig. 1 and comprises a bed 46 for supporting the die and a reciprocating presser member 48 arranged to descend upon the mask plate to force a blank such as blank 18 downwardly over the edges of the punch tube 12.

In the operation of the device, when it is desired to perforate a right blank such as blank 18, the mask plate 16 is tilted about its hinge 36 and the blank 18 is placed upon the stripper plate 14 with the portion to be perforated approximately positioned above the punch tubes 12. The mask plate 16 is then rotated about its pivot 34 to bring the right blank gaging portions 32 adjacent to the punch tubes and the plate is lowered to bring the opening 44 over the pin 42, thus accurately locating the plate and securing it in operative position. The blank 18 is then adjusted to bring its edge portions into alignment with gaging portions 32 of the mask plate, thus accurately locating the blank relatively to the punch tubes after which the presser member 48 is brought down upon the die to perforate the blank. A similar procedure is followed with left blanks except that the gaging portions 30 are located adjacent to the punch tubes 12 by positioning the plate 16 with the opening 45 surrounding the pin 42. Thus it will be apparent that I have provided a die which is readily adaptable to operation upon either left or right blanks by the simple process of varying the position of the blank gaging means.

Having described my invention, what I claim as new and desire to secure by Letters Patent of the United States is:

1. A die for ornamenting shoe part blanks comprising a plurality of punch tubes, a work support overlying the punch tubes, and gaging means mounted upon the work support for movement selectively into position for locating either

a right or a left blank in predetermined position relatively to the punch tubes.

2. A die for ornamenting shoe part blanks comprising a base, punch tubes carried by the base, a work support mounted upon the base and overlying the punch tubes, gaging means carried by the work support and movable selectively into position to locate either right or left blanks relatively to the punch tubes, and means for securing the gaging means in either of its selected positions.

3. A die for ornamenting shoe part blanks comprising a base, punch tubes mounted upon the base, a work support adjacent to the punch tubes and resiliently mounted upon the base, and a mask plate hingedly and pivotally mounted upon the work support and having gaging portions for locating either right or left blanks in operative position relatively to the punch tubes.

4. A die for ornamenting shoe part blanks comprising a base, punch tubes carried by the base, a stripper plate for supporting a blank above the punch tubes, a mask plate having gaging portions, and means for mounting the mask plate upon the stripper plate for angular movement relatively thereto to provide for insertion of a blank and for movement laterally of the stripper plate into positions to locate the gaging portions in different positions relatively to the punch tubes.

5. A die comprising a base, punch tubes mounted upon the base, a stripper plate resiliently mounted upon the base and having an opening through which the punch tubes can operate, a mask plate associated with the stripper plate and having a plurality of openings of greater area than that corresponding to the punch tubes and gaging means associated with each of the openings, and means for mounting the mask plate for movement into positions to locate either of the gaging means in operative position relative to the punch tubes.

6. A die comprising a base, punch tubes carried by the base, a stripper plate yieldingly mounted upon the base and having an opening therein through which the punch tubes can operate, and a mask plate hingedly and pivotally mounted upon the stripper plate and having a plurality of gaging means movable with the mask plate selectively into positions for locating either left or right blanks on the stripper plate in operative position relatively to the punch tubes.
